LEASING MECHANISM FOR TEXTILE MACHINES

Thomas F. Suggs, Gastonia, N. C., assignor to Cocker Machine & Foundry Company, Gastonia, N. C., a corporation of North Carolina

Application February 20, 1957, Serial No. 641,288

6 Claims. (Cl. 28—40)

This invention relates to leasing mechanism for textile machines used in the preparation or treatment of multiple yarns in which the yarns are drawn from supplies by a pair of opposed nip rolls and delivered to the elements of the machines whereby the treatment of the yarns is effected.

The chief aim of my invention is to provide a simple and reliable leasing mechanism by which the leasing is accomplished quickly and easily just prior to entry of the yarns between the nip rolls. Briefly described, my invention comprises a pivoted leasing reed which is shaped to conform, when in normal inoperative position, to the configuration of the entrant bight of the draft rolls, said reed having in alternate dents thereof, pairs of closely-spaced stops between which alternate yarns are passed, so that upon swinging of said reed to an angular position, the alternate yarns are displaced laterally relative to the other yarns by one set of the stops to form a shed for introduction of a leasing thread, and an associated independently pivoted cooperative element, which upon movement from its normal position causes both yarns to be shifted, with incidental arresting of the alternate yarns by the other group of stops to form a reverse shed for introduction thereto of a second leasing thread.

Other objects and attendant advantages will appear from the following detailed description of the attached drawings, wherein:

Fig. 1 is a view in top plan of a yarn crimping machine conveniently embodying the leasing mechanism of my invention.

Fig. 2 shows the machine in side elevation.

Fig. 3 is an end elevation of the machine viewed from the right of Figs. 1 and 2.

Fig. 4 is a broken out fragmentary plan view of the leasing reed drawn to a large scale.

Figs. 5—8 are fragmentary views in longitudinal section showing successive sequential steps in effecting a leasing operation in accordance with my invention.

Figs. 9 and 10 are fragmentary detail views in section taken as indicated respectively by the angled arrows IX—IX and X—X in Figs. 5 and 7.

With more specific reference, first more especially to Figs. 1—3 of these illustrations, the numerals 10 and 11 designate a pair of horizontally-arranged nip rolls by which yarns Y and Y' to be crimped are drawn from supplies, not shown, through a collecting eye board 12 and an ordinary spacing reed 13 and delivered to a crimping means generally indicated at 14. The shaft 15 of the roll 10 is journaled in bearings 16 fixed in laterally spaced longitudinal side frames 17 of the machine upstanding from a bed 18; while the shaft 19 of the roll 11 is journaled in bearing blocks 20 which are slidable in horizontal guideways 21 provided by said side frames. The roll 11 is yieldingly urged toward the roll 10 by means of a spring 22 which bears centrally against a transverse bar 23 connecting rearward projections 24 on the bearing blocks 20, the pressure of said spring being regulatable by means of a screw 25 threadedly engaged in a lug 26

2

on the bed 18 and provided at its outer end with a manipulating hand wheel 27. As shown in Fig. 1, the roll shaft 15 is arranged to be positively driven through a sprocket wheel 28 and chain 29 from a motor (not illustrated); and through a pair of intermeshing spur gears 30 and 31, said shaft communicates motion to the roll shaft 19 so that the rolls 10 and 11 are driven contrariwise in unison as indicated by the arrows in Figs. 2 and 5—8.

The leasing mechanism with which the present invention is more particularly concerned comprises a leasing reed which is comprehensively designated 35, and which is fixed upon a transverse shaft 36 journaled in stationary bearing blocks 37 on the tops of the side frames 17 to one side of the rolls 10 and 11. The leasing reed 35 is made up of laterally spaced blade elements 38 struck from thin stiff sheet metal or the like, said elements being welded or otherwise rigidly connected to the shaft 36 and being united at their distal ends by a cross rod 39. As shown in Fig. 2, the elements 38 are V shaped with the sides of the V rounded concentrically with the curvatures of the rolls 10 and 11 to correspond to the configuration of the upper bight between said rolls. It is to be particularly noted that when the leasing reed 35 is in the normal position of Fig. 2, the pointed junctures of the arcs of the component elements 38 are disposed within the upper bight of said rolls without contacting the latter. Set, for a purpose presently explained, into the alternate spaces or dents of the leasing reed 35 equally distant from the center points of the elements 38, are pairs of closely spaced stop blocks 40 and 41. The shaft 36 is operable by means of a hand lever 42, and to it are affixed, adjacent the inner sides of the bearing brackets 37, disks 43 having annularly-spaced indentations 44 and 45 in the contiguous faces thereof for selective engagement by spring plungers 46 lodged in said bearing brackets to keep the leasing reed 35 either in its normal or operative positions as also more fully explained presently.

The leasing mechanism of my invention further includes an arm 50 which normally occupies the position in which it is shown in Figs. 1 and 2, said arm being fixed upon one end of a short transverse shaft 51 which is disposed at the opposite sides of the rolls 10 and 11 and is rotatively supported in a bearing bracket 52 pendent from the bed 18 of the machine. At its upper or distal end, the arm 50 has a rod 53 that extends crosswise of the machine and serves as a guide over which the yarns Y and Y' pass enroute to the rolls 10 and 11. For ease of manipulation, the arm 50 is provided with a grasp handle 54. The arm 50 is yieldingly held in the normal position of Figs. 2 and 3 by engagement of a spring plunger 55 engaged in the central one of three indentations 56, 57 and 58 in a sector 59 secured to the opposite end of the rock shaft 51.

Operation

With the arm 50 and the lease reed 35 normally positioned as in Fig. 2, it will be seen that the yarns Y and Y' will be directed vertically down to the rolls 10 and 11 and maintained in definite separation by the downward pointed portions of the components 38 of said lease between which said yarns pass until just before entering the bight of said rolls. When a lease is to be made, the machine is stopped. Thereupon the reed 35 and the arm 50 are swung to the positions in which they are shown in Figs. 5 and 9, in which positions they are latched by engagement of the spring pressed plungers 46 in the indentations 44 of the disks 43 on shaft 36, and of the spring pressed plunger 55 in the indentation 58 of the sector 59 on shaft 51. As a result, the segments of the yarns Y' between the rod 53 and the rolls 10 and 11 are engaged by the stops 41 in the alternate dents of the leasing reed 35 and are displaced laterally to the left of the corresponding segments of the yarns Y in the inter-

mediate dents of said reed. A shed S is thereby formed through which a lease thread T is inserted. With this accomplished, the arm 50 is swung counterclockwise through the position of Fig. 6 until stopped in the position of Fig. 7 by engagement of the spring plunger 55 into the indentation 56 in the sector 59 on shaft 51. As the arm is so swung the segments of the yarns Y are displaced leftward with incidental arresting of the yarns Y' by the stops 40 of the reed 35 and formation of a reverse shed S' through which a second leasing thread T' is introduced as in Figs. 7 and 10. Finally, the arm 50 is restored to the normal position of Fig. 8, and the leasing reed 35 to the normal position of Fig. 2, whereupon the machine is re-started to proceed with the crimping of the yarn as before.

While for the purposes of exemplification herein I have shown and described my improved leasing mechanism in connection with a crimping machine it is not to be considered as limited to such application since, by suitable modifications within the scope of the appended claims, it is equally adaptable to other types of textile machines such as slashers and the like.

Having thus described my invention, I claim:

1. Leasing mechanism for a textile machine including in combination, a pair of opposed rolls; a guide rod over which plural yarns are passed and directed into the nip of the rolls; and means operative to displace segments of alternate yarns between the guide rod and the nip of the rolls laterally relative to corresponding segments of the intervening yarns in one direction to form a shed for insertion therein of a leasing thread, and thereafter to displace the segments of the alternate yarns in the opposite direction relative to the corresponding segments of the intervening yarns to form a reverse shed for insertion therein of a second leasing thread.

2. Leasing mechanism for a textile machine including in combination, a pair of horizontally arranged opposed rolls; an arm pivotally supported adjacent the rolls at one side thereof and provided at its distal end with a transverse rod high above the rolls, over which a sheet of yarns is guided to pass vertically, into the nip of the draft rolls; and a reed pivotally supported adjacent the rolls at the other side thereof and normally positioned horizontally

immediately above the rolls with the yarns passed through the dents thereof, alternate dents of the reed respectively having therein pairs of closely spaced stops between which alternate yarns pass whereby, upon upward movement of the reed to angular position, segments of alternate yarns between the guide rod and the rolls are intercepted by one group of the stops and corresponding segments of the intervening yarns are relatively displaced laterally to form a shed for the introduction thereinto of a leasing thread, and whereby, upon movement of the guide rod arm through an acute angle toward the reed, the segments of alternate yarns are intercepted by the other group of stops and the corresponding segments of the intermediate yarns are relatively displaced laterally in the opposite direction to form a reverse shed for introduction thereinto of a second leasing thread.

3. Leasing mechanism according to claim 2, further including means for releasably holding the guide rod arm and the reed selectively in their normal and leasing positions.

4. Leasing mechanism according to claim 2, wherein the reed is affixed to a transverse shaft journaled in stationary bearings, and wherein a disk secured to said shaft has a pair of annularly-spaced indentations adapted to be selectively engaged by a spring-pressed plunger lodged in one of the bearings to hold the reed yieldingly in its normal and leasing positions respectively.

5. Leasing mechanism according to claim 2, wherein the guide rod arm is affixed to a transverse shaft journaled in stationary bearings, and wherein a sector secured to said shaft has a pair of annularly-spaced indentations adapted to be selectively engaged by a spring-pressed plunger lodged in one of the bearings to hold said arm yieldingly in its normal and leasing positions respectively.

6. Leasing mechanism according to claim 2, wherein the reed is formed by multiple bars fashioned from thin sheet material and shaped to conform with the configuration of the upper bight between said rolls.
